DOOR CHECK

Henry Singer, Honolulu, Territory of Hawaii

Application February 11, 1944, Serial No. 522,004

5 Claims. (Cl. 16—86)

This invention relates to a door check and it is an object of the invention to provide a device of this kind which, in addition to its primary purpose of preventing noisy slamming of doors, provides means to hold the door partly open for ventilation or for the easy entry of small children and house pets.

Another object of the invention is to provide a device of this kind of an overhead type which assures the same being in a position to eliminate stumbling as well as the necessity of a person stooping or bending over when necessary to adjust the same.

The invention consists in the details of construction and in the combination and arrangement of the several parts of my improved door check whereby certain important advantages are attained, as will be hereinafter more fully set forth.

In order that my invention may be better understood, I will now proceed to describe the same with reference to the accompanying drawing, wherein:

Figure 1 is a fragmentary view in elevation illustrating a door check constructed in accordance with an embodiment of my invention in applied position, the associated door frame being in fragment;

Figure 2 is an enlarged detail sectional view taken substantially on the line 2—2 of Figure 1, the closed position of the door being indicated by broken lines; and

Figure 3 is an enlarged elevational view with a portion in section of the check as herein embodied, the line of section being substantially on the line 3—3 of Figure 1.

As disclosed in the accompanying drawing, B denotes an elongated body member of desired dimensions and which, when applied, has a flat end a butting the upper portion of a door frame with the body B extending outwardly therefrom in the same general direction in which the door D swings. This body B may be anchored in place in any desired manner but, as shown in the accompanying drawing, such securing is obtained by the use of the brackets 1 secured to both the body member B and the door frame F by the screws 2 or otherwise as may be preferred.

The body member B, when applied, is positioned in close proximity to the door opening and the longitudinal face b of the body member B immediately adjacent to the door opening is provided therealong with a series of longitudinally spaced sockets or recesses 3 in each of which is snugly fitted the solid end portion c of an elong-

ated block or slab 4 of rubber material possessing the desirable pliable or flexible resistance but which normally maintains a substantially fixed formation.

The block or slab 4 is of a length, when applied, to extend a material distance beyond the face b of the body member B and said extended portion is slit, as at d, at points spaced transversely of the block or slab 4 to provide the leaf members 5. These leaf members 5 extend within the path of a free marginal portion of the door as it swings into either open or closed position and the leaf members 5, while particularly retarding the closing movement of the door D, also provide means whereby the door D may be effectively held in a partly open position, particularly when the door is engaged between adjacent blocks or slabs 4 and which is particularly desirable for ventilation and to allow for the entry of small children and house pets. It is believed to be apparent that when a marginal portion of the door D is engaged between adjacent blocks or slabs 4, the door will be held in a partially open position until forcibly moved.

By having the extended portion of each of the blocks or slabs 4 in the nature of leaves 5, the liability of the door D becoming stuck when being swung into either open or closed position is substantially eliminated as these leaves 5 afford increased pliability and hence offer less resistance although it is to be stated that each leaf 5 helps to act as a brake to check the speed of the swinging or closing door, thereby preventing a noisy slam. The efficiency of these leaves 5 is further increased by having such leaves 5 of each block or slab 4 successively of increased length with the shorter leaf outermost.

Each of the blocks or slabs 4 may be secured or held within its socket 3 in any manner desired but I find it of particular advantage to provide the solid inserted end portions c of these blocks or slabs 4 with the openings 6 extending transversely therethrough which register with the longitudinally disposed opening 7 extending through the body member B at substantially its axial center. This permits the insertion through the body member B and the portions c of the blocks or slabs 4 of an elongated holding shank 8, one end portion being provided with a fixed head 9 which is received by a counterbore 10 preferably at the inner end of the body member B while the opposite end portion of the shank 8 has threaded thereon a holding nut 11 which contacts with the adjacent or outer end of the body member B. It is believed to be obvious that upon

removal of the shank 8, a block or slab 4 can be readily removed and replaced as the requirements of practice may find necessary.

In view of the foregoing it is believed to be readily apparent that my improved door check is one which can be used at the upper portion of a door frame so that the same will be overhead and out of the way, thus eliminating the liability of a person stumbling over the type of checks now frequently used which are positioned at the bottom portion of the door frame.

With the device as herein disclosed, it is also unnecessary for a person to bend or stoop over when it is required in any way to adjust the check and with the further advantage of substantially eliminating the liability of the device being interfered with by children and house pets.

The body B may be made of wood, metal or any material deemed suitable.

From the foregoing description it is thought to be obvious that a door check constructed in accordance with my invention is particularly well adapted for use by reason of the convenience and facility with which it may be assembled and operated.

What is claimed is:

1. A door check comprising a body member to be placed adjacent to a door opening, and a plurality of means carried by the body member and extending within the path of travel of a marginal portion of a door swinging into open or closed position with respect to the door opening to successively retard the closing movement of the door or to hold the door in a partly open position, each of said means comprising a series of separate resilient members with adjacent members of the series in close relation.
2. A door check comprising a body member to be placed adjacent to a door opening, and a plurality of separable pliable elements extending

outwardly from the body member at points spaced therealong and of a length to intersect the path of travel of a marginal portion of a door swinging toward or from the door opening.

3. A door check comprising a body member to be placed adjacent to a door opening, and pliable elements extending outwardly from the body member at points spaced therealong and of a length to intersect the path of travel of a marginal portion of a door swinging toward or from the door opening, the extended portions of the elements with which the door contacts constituting leaves arranged side by side.

4. A door check comprising a body member to be placed adjacent to a door opening, and pliable elements extending outwardly from the body member at points spaced therealong and of a length to intersect the path of travel of a marginal portion of a door swinging toward or from the door opening, the extended portions of the elements with which the door contacts constituting leaves arranged side by side, and successively of differing lengths with the shorter leaf farthest from the door opening.

5. A door check comprising an elongated body member for securement adjacent to a door opening, said body member having a face provided with longitudinally spaced sockets, blocks of pliable material having end portions held within the sockets, said blocks being of a length to extend beyond the body member into the path of travel of a marginal portion of a door swinging toward or from the door opening to successively retard the closing movement of the door and to provide means, when a marginal portion of the door is between the extended portions of two adjacent blocks, to hold the door in a partly open position.

HENRY SINGER.
